(57) **CLAIM**

I claim the ornamental design for a magazine release button, as shown and described.

DESCRIPTION

FIG. 1 is a top plan view of a magazine release button, showing my new design;

FIG. 2 is a rear-left side perspective view thereof;

FIG. 3 is a front-left side perspective view thereof;

FIG. 4 is a front view thereof;

FIG. 5 is a rear-side perspective view thereof; and,

FIG. 6 is a bottom view thereof.

The broken lines in the drawings depict unclaimed portions of the magazine release button only and form no part of the claimed design.
